CLAIM

The ornamental design for a stone mortar and pestle set, as shown and described.

DESCRIPTION

FIG. 1 is a first perspective view of a stone mortar and pestle set showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a second perspective view thereof.

FIG. 9 is a third perspective view thereof.

FIG. 10 is a fourth perspective view thereof.

FIG. 11 is a first perspective view of the pestle of the stone mortar and pestle set shown removed from the set for clarity of disclosure.

FIG. 12 is a front view thereof.

FIG. 13 is a rear view thereof.

FIG. 14 is a left side view thereof.

FIG. 15 is a right side view thereof.

FIG. 16 is a top view thereof.

FIG. 17 is a bottom view thereof.

FIG. 18 is a second perspective view thereof.

FIG. 19 is a first perspective view of the lid of the mortar of the stone mortar and pestle set shown removed from the set for clarity of the disclosure.

FIG. 20 is a front view thereof.

FIG. 21 is a rear view thereof.

FIG. 22 is a left side view thereof.

FIG. 23 is a right side view thereof.

FIG. 24 is a top view thereof.

FIG. 25 is a bottom view thereof.

FIG. 26 is a second perspective view thereof.

FIG. 27 is a first perspective view of the mortar of the stone mortar and pestle set shown removed from the set for clarity of the disclosure.

FIG. 28 is a front view thereof.

FIG. 29 is a rear view thereof.

FIG. 30 is a left side view thereof.

FIG. 31 is a right side view thereof.

FIG. 32 is a top view thereof.

FIG. 33 is a bottom view thereof; and,

FIG. 34 is a second perspective view thereof.
